UNITED STATES PATENT OFFICE.

JOHN D. PEDERSEN, OF JACKSON, WYOMING.

FIREARM.

1,333,571.

Specification of Letters Patent.

Patented Mar. 9, 1920.

Application filed December 29, 1917, Serial No. 209,485. Renewed July 31, 1919. Serial No. 314,427.

To all whom it may concern:

Be it known that I, JOHN D. PEDERSEN, a citizen of the United States, residing in Jackson, in the county of Lincoln and State 5 of Wyoming, have invented certain new and useful Improvements in Firearms, of which the following is a specification.

This invention relates to that class of firearms in which the barrel is without longitudinal movement relative to the frame, but is 10 detachably united thereto, and relates more especially to small-arms in which the sliding bolt-carrier or breech-block thereof is arranged for being locked in retracted or 15 "open" position by means of a slide-lock actuatable into a slide-engaging position by a spring-actuated magazine follower.

My present improvements are especially applicable to those kinds of small-arms 20 which are provided with magazines having spring-actuated followers, or cartridge-feeders, and particularly to that class of these small-arms which are commonly known as auto-loading pistols.

25 One of the principal objects of the invention is to furnish for use in said class of firearm mechanisms, a simple and effective device whereby the barrel may be detachably united with the frame by means of a 30 transverse bar which in addition to directly uniting the barrel to the frame, shall also be directly coactive with the breech-slide for holding in place and releasing this barrel-holding bar; and, whereby such a cross-bar,—having the form of a shaft,—shall be 35 combined with a slide-lock member which may be continuously subjected to a frictional regulation or control by a force derived from the breech-slide-actuating spring and trans- 40 mitted to such slide-lock through the barrel and said cross-bar, or shaft.

In the accompanying drawing forming a part of this specification, my present improvements are illustrated as applied to an 45 auto-loading pistol, of which only the upper portion is shown, but sufficient for illustrating the arrangement and mode of operation of the features and devices hereinafter described.

50 Figure 1 is a side view or elevation of the upper portion of an auto-loading pistol having my present improvements applied thereto in a preferred form and arrangement thereof; in this view the "bolt-carrier", or

breech-slide, S, is shown in its forward or 55 firing position, on the frame F;

Fig. 2 is a side elevation similar to and drawn in alinement with and below Fig. 1, but showing the breech-slide retracted to about the usual loading position; in this 60 view the slide S is shown locked in its retracted position by the slide-stop arm d, as hereinafter more fully explained;

Fig. 2^a is a fragmentary side view corresponding to a mid-length portion of Fig. 2, 65 for showing the position of the slide S for permitting the withdrawal of the member C, as hereinafter explained;

Fig. 3 is a sectional side view of the left-hand portion of the firearm, and is drawn 70 below and in alinement with Figs. 1 and 2 for facilitating comparison therewith;

Fig. 4 is a plan view of so much of the forward part of the firearm as is shown in Fig. 3, but with the slide S and barrel B, 75 (also a small portion of the frame F), broken away in some portions thereof for more clearly exhibiting such details as are comprised in or immediately related to my present improvements.

80 Figs. 4^a and 4^b are fragmentary views for illustrating certain modifications of minor details, and are hereinafter more fully explained;

Fig. 5 is a cross-section taken on the line 85 X⁵ of Fig. 3, for showing in a side view thereof and in working position, the cross-bar or shaft, C, whereby the barrel and frame are detachably united;

Fig. 5^a is a cross-section similar to Fig. 5, 90 for illustrating a modified form of said cross-shaft C;

Fig. 6 is a sectional plan view,—similar to the right-hand portion of Fig. 4,—for illustrating a modification in the organization 95 and arrangement, and in the mode of action of the slide-stop means with relation to the frame, F, barrel, B, and slide, S, of the fire-arm mechanism, and which may be adopted in connection with a frame-and-barrel uniting cross-bar which does not carry a slide-stop arm;

Fig. 7 is a fragmentary side view,—similar to Fig. 2^a,—for further illustrating the said modified arrangement shown in Fig. 6; 105 for this purpose, Fig. 7 is drawn below and in alinement with Fig. 6;

Fig. 8 is a plan view of the form of com-

2 bined shaft and stop-arm, C, shown in Figs. 1 to 5, inclusive; and Fig. 9 is a view of said member C, as seen from below in Fig. 8.

Similar characters designate like parts in 5 all the views.

In the accompanying drawings, my present improvements are illustrated as applied to a firearm mechanism which is organized substantially as set forth in my copending 10 application, Serial No. 204,149, filed November 27, 1917. This mechanism, in the form thereof selected for illustration herein, comprises the three principal members of an auto-loading pistol, the frame, the bolt- 15 carrying slide, and the barrel; these members are herein designated in a general way by F, S, and B, respectively. Only the upper portion of the frame, F, is shown, and the particular design which is illustrated, 20 has been selected merely for the purposes of illustration, and because it may be considered as typical of various other such frames which are already well-known in this art.

25 The bolt-carrying breech-slide, S, is shown slidably mounted on the frame F by means of ordinary interengaging ribs and grooves; these are clearly shown in the sectional views Figs. 3 and 4, and being 30 already common in the art, do not now require a particular description. The forward portion of the slide S,—at the left-hand in Figs. 1 to 4,—is shown formed with an interior barrel chamber, 3^a, and as having 35 in section, (Fig. 5), a customary inverted-U shape, so that the slide, at the section indicated, may be said to comprise a top-wall, (usually curved about as shown), and the two depending side-walls, 3^c, 3^{c'}, which extend 40 downwardly to a position somewhat lower than the bore of the barrel. In one of these side-walls,—in this instance, the slide-wall 3^c,—there is formed a recess or gate-way space, as 2, for a purpose herein- 45 after explained.

The barrel, B, is shown inclosed within the slide-chamber 3^a, excepting that the forward end, 2^a, is shown slidably supported in a well-known manner in a ring or bearing, 3^d, which is removably fixed in the forward end of said slide member, so that said end-portion, 2^a, may be said to extend outwardly, in a forward direction from said chamber 3^a. The rear end, 2^b, of the barrel 50 B is shown enlarged to nearly fill, transversely, said chamber 3^a, and thus also to form at 2^c, a shoulder, between which the said bearing 3^d, the slide-actuating spring, N, is held under suitable compression.

60 The particular style or variety of "slide", S, which is herein illustrated, is shown as being one of that well-known class of sliding breech-bolt carriers which are removable from the frame in a forward direction 65 only; hence, I have herein shown that slide

formed and arranged for having the barrel, B, inserted therein (in a well-known manner not herein shown) while the slide is off from the frame, so that these two members, S and B, after being thus preliminarily assembled together may be then together slid into place in the usual manner, from the front of the frame. Said slide may have the usual perforated breech-bolt face, as f, (partially shown in Fig. 3), and may also 70 carry an ordinary firing-pin, the point of which is indicated in a well-known form at f².

The barrel and frame are shown releasably-united by means of an improvement 80 which forms in part the subject-matter of my said copending application, Serial No. 204,149. In that application, the barrel and frame are provided with interengaging portions and with a fastening which together 85 constitute a device in the nature of an interlock. In accordance with the principle and method described in said prior application, the frame F, is herein shown having formed therein the recess a³, and the barrel B is 90 shown provided with a downward extension, b', which in practice may have any proportions convenient and suitable for the particular size and shape of the recess. Said depending portion b' of the barrel, 95 should of course, fit rather closely between the side walls of the recess (see Figs. 4 and 5); so that the rearward end 2^b of the barrel will be held in place with a proper degree of rigidity. When the barrel, 100 being thus fitted, is put in place on the frame, these two members are then strongly united by means of a transverse bar, as C, which is fitted into the cross-bar seat, at a⁴, of the frame, and into the similar seat, at b², of the 105 barrel; these seats thus forming, in effect, transverse and aligned cross-bar seats,—in this instance, cross-shaft seats,—which extend through the frame and are positioned partly above and partly below the plane of 110 the lower edge of the bar-retaining means which is appurtenant to the slide.

While tenon-and-cross-bar connections of this general class are a well-known mortise-joint of barrel-attaching means, especially 115 in shoulder arms, yet, in my present improvements, the cross-bar has a different position and construction, and thus operates and directly coacts in a new way in combination with the sliding bolt-carrier, 120 and with a slide-lock device of an auto-loading firearm having a non-reciprocating barrel. In the construction herein illustrated, it will be seen that on withdrawing the cross-bar, or cross-shaft, the barrel is 125 removable from the frame by a sliding movement and in a forward direction only.

In the operation of the mechanism, the cross-bar C receives by direct contact, and receives transversely thereto, the rear- 130

wardly acting pressure of the barrel under the recoil, and also the pressure of the spring N, as transmitted thereto through the barrel; and, as regards the sustaining 5 of these transversely-applied forces, said cross-bar does not have imparted thereto any turning movement or tendency to rotate. Furthermore, said cross-bar does not have in the assembled mechanism the function of a pivot in relation to any of the 10 members, since the barrel alone is separably supported thereon, and since the barrel has no turning or other movement with relation to the cross-bar or to the frame during the operation of the mechanism.

When the barrel-and-frame-uniting cross-bar is also to be employed as the arm-carrying shaft,—see Figs. 1 to 5^a, inclusive,—this combined cross-bar and shaft is preferably made in the form of a cylinder, this 20 form being, of course, the more simple and convenient. This form of said member C is one of the forms thereof set forth in my said application, Serial No. 204,149, and 25 the preferable construction thereof may be described, briefly, as follows:

In the drawings, the shaft-form cross-bar C is shown located sufficiently high in the frame so that,—when the firearm is held 30 horizontally in normal position as in Fig. 1,—the upper side of the cylindrical surface or seat a⁴ is above the plane of the lower edge 3^t, of the side-wall, 3^c, of the slide. Thus the shaft-member C and said lower 35 edge 3^t may be said each normally to intercept or interfere with the other; but an actual interference is avoided by making and arranging said member C in the following manner:

40 As seen in a side view thereof, (see Figs. 5 and 9), the shaft C has the end-portions c², c³, thereof reduced in size,—and hence, of a notched construction,—being thus shaped so that when the mechanism is assembled, said end-portions will extend and lie closely underneath the coactive slide-walls 3^c, 3^{c'}, respectively. Thus the said full-length form of the shaft C has the two surfaces c⁴, c⁵, which are disposed longitudinally thereof, and should be just out of contact with the lower-edge surfaces 3^t, 3^{t'}, respectively, of the slide S. In Fig. 5, the position of the plane of said surfaces c⁴, c⁵, is shown by a medial line, as y, which line, 50 preferably and usually, in practice, should be located about or approximately midway of the height of the shaft or cross-bar, thus bringing all that part thereof which lies above said mid-plane line y thereof, into a 55 position directly between said side-walls of the slide S; as clearly indicated in Figs. 2^a and 5. This construction and arrangement also provides for making on the shaft, a pair of vertically-disposed and outwardly-facing faces, or surfaces, as c⁶, c⁷, which are

in positions adjoining the sides, respectively, of the frame F, and are located in a direction transverse to the shaft, and also to said plane, y, of the faces c⁴, c⁵. Said surfaces c⁶, c⁷, are therefore each in a position for 70 coacting with one of the inwardly-facing surfaces or faces, at 3^h, 3^{h'}, (Fig. 5), of the slide-walls 3^c, 3^{c'}. Said transverse surfaces c⁶, c⁷, positively prevent said bar from having any undue endwise movement in either 75 direction.

In order to provide for inserting and withdrawing said arm-shaft when this member is constructed and positioned as here explained, the slide-wall adjacent to the 80 stop-arm, d, (in this instance, the wall 3^c), may have the continuity thereof terminated or interrupted at a point or position for permitting the withdrawal of the shaft out of the shaft-seat, when the slide is in some one 85 position in the stroke thereof. This object may be accomplished by forming a recess or gate-way space, as 2, (Figs. 1, 2, 2^a), in such a position in said shaft-retaining side-wall that when the slide is at some convenient 90 point between the ends of its travel, or working stroke, (see Fig. 2), this recess will come into alignment with said shaft-seat, a⁴, of the frame, and thereby permit the body of the shaft to be pushed or drawn 95 out through said recess as through a door or gate-way therefor.

In some instances, if desired, instead of cutting out a recess in the said depending and shaft-retaining slide-wall, as 3^c, 100 such wall may have, as to such shaft-retaining portion thereof, its continuity of length limited in one direction for thereby permitting the withdrawal of the body of the shaft (Figs. 4, 5), outwardly past said slide-wall when the slide is in some one, (or in a sufficiently retracted), position thereof; this retracted position, in practice, may be at or near the rearward end of the working stroke of the slide. One such limit of continuity of length is shown at 3^t, Figs. 2 and 2^a, this being the point where, in the present instance, a shaft-retaining portion of the slide-wall 3^c is shown to be terminated, or discontinued, in the forward direction. Thus, such a slide-wall of limited 110 length, may be considered as being one means appurtenant to the slide and in position and arranged for coacting with a transverse face, as c⁶, of the shaft C, during one portion of the reciprocating movement of the slide, and for withdrawing from such coacting position during a further movement of the slide.

In practice, it is deemed desirable that 125 the recess or gate-way, 2, should be so located as not to be in front (as in Fig. 2^a) of the face or shoulder c⁶ of the shaft when the slide S is in either the forward or the fully retracted position; 130

thus the user, when desiring to take out the shaft, will be required to draw the slide backwardly from its position in Fig. 1, for only a short distance, in order to bring said space 2 into the shaft-releasing position shown in Fig. 2^a. This arrangement has also the advantage that in the normal operation of the firearm, said gate-way recess 15 will pass by the shaft C while the slide S is moving at a high velocity, thereby safeguarding the operation. A further safeguard is also secured, since the parts may be fitted so that the force of the spring N, and the action of the recoil, will apply pressure to the shaft C during the time the recess 2 is passing this shaft, (Fig. 2^a), and thus will tend to hold the shaft so firmly as to prevent any longitudinal movement during such a brief time-interval.

20 For permitting the shaft C to have the small but proper amount of turning movement to provide for the working stroke of the slide-stop arm d, the upper face c⁵, of the reduced end c⁴ of said shaft, is so reduced or positioned as to provide a small, but proper amount of space at e², (Fig. 5), so that the shaft may turn slightly without causing said end portion c⁴ of the shaft to bear, or bind, against the lower surface, 3¹, 30 of the shaft-retaining slide-wall 3².

In Figs. 4 and 5, the cross-shaft C is shown with the stop-arm d fitted to lie close against the outside surface 2¹, of the frame F, so that in practice said cross-shaft will 35 normally be held against longitudinal movement by the coaction of the inner surface c³ of said arm and the transverse surface c⁶, which is located close to the vertically-disposed inner surface 3³ of the slide-wall 3². 40 When the cross-shaft is thus provided with the two movement-limiting surfaces c⁵ and c⁶, the opposite end thereof, c⁴, may be omitted, and also said shaft may terminate at a point just within the frame; this omission is shown in the modified arrangement 45 illustrated in the sectional view Fig. 5^a. In this arrangement, in practice, the bar-seat or bore in the frame, for receiving said cross-bar, need not extend entirely through 50 the frame, but there may be a thin wall as 2⁴, between the outer surface of the frame and the inner end of the cross-shaft, so that this shaft will not then be accessible from that side of the frame which is opposite to 55 the said arm d, thereof.

On account of the ordinary mode of taking the pistol in hand, it will usually be desirable to have said cross-shaft and stop-arm so arranged that the stop-arm will be 60 in a position at the left-hand side of the pistol frame, and this, it will be understood, is the arrangement herein illustrated. However, it will be evident without further illustration, that in constructing the parts, 65 these may be arranged in a reverse manner

(not herein shown) should occasion require, so that the cross-shaft will have the stop-arm at the right-hand side of the frame.

In my present improvement, as will now be evident, the cross-shaft member C does 70 not need to be turned preliminarily to the withdrawal thereof, but when the slide, S, is moved to bring the recess or gateway 2 into alinement with said member C, (see Fig. 2^a), this member may then be drawn 75 directly outward toward the right-hand in Fig. 5; this operation (except as to the modification of Figs. 6 and 7), frees the barrel and the frame each from the other, except as to the engagement of the afore- 80 said depending part of the barrel within the recess or mortise of the frame. That outward movement, however, of said cross-shaft is effectually prevented at all times 85 during the normal operation of the firearm, because then the sliding bolt-carrier S is always moving either forwardly or rearwardly whenever said gateway 2 is at or adjacent to said cross-shaft member.

The cross-bar or shaft C, in practice, 90 should be made large enough so that the arm-carrying portion c² thereof will have the strength needed for safely carrying said arm and for sustaining any strains 95 which may arise from the work to which such arm may be subjected.

In order to bring the transverse face c⁶ of the cross-shaft into position for coacting,—as a sliding face,—with the inner surface 3³ of the slide wall c³, said cross-shaft 100 is shown so located that the plane of said wall-surface 3³ will come near to a mid-plane, y, of the shaft; this arrangement also brings into a position directly between the slide-walls c³ and c³', (Fig. 5), all that 105 part of said cross-shaft which lies above said mid-plane thereof, so that the transverse faces of said shaft (when the shaft has two such faces) come into proper co-acting relation, respectively, with the afore- 110 said inner wall-surfaces 3³, 3³'.

Since one purpose of the mid-length portion, as c⁶, (Figs. 2^a, 5), of the surface of the round shaft C is to provide sufficient area whereby to obtain a proper or effective 115 amount of frictional control of the lever-arm d, therefore,—in practice, and in some instances,—the diameter of said shaft may be made larger than required merely for strength as a barrel-and-frame uniting cross-bar. Thus said mid-surface at c⁶ is in the nature of a friction-drum appurtenant to a shaft-form bar whereby the constantly acting spring-pressure, when applied thereto in such a manner as already explained, may 120 duly restrain the movement of the lever or stop-arm d.

A further advantage secured by the present arrangement, is that the working movements of the stop-arm have no effect, at any 130

time, on the extent of the engagement of the surfaces by which the stop-arm is retained in proper working-position laterally of the frame. The lower edge 3^t of the 5 slide-wall 3^c usually will be parallel, of course, to the direction of sliding movement of the slide S. Therefore, the area of that portion of the stop-surface c^a of the cylindrical shaft C, which lies above said slide-wall edge, or line 3^t, will be of a constant extent, and not modified by the turning of the shaft within the normal range of said working movements. Thus in practice, no 10 excess or amplification of said area of engagement needs to be provided for, in order to have at all times a sufficiently large area of actual engagement.

The up-stroke of the stop-arm,—Fig. 2,—is limited, naturally, by the lock-end 4^a engaging (with) in the notch 2 of the slide, so that the slide-wall c^a may be said itself to act as the up-stroke-limiting means. An 15 analogous arrangement may also be employed, and preferably in some instances, for limiting the down-stroke of the stop-arm. For instance, in Figs. 6, 7, the arm d is shown with a portion, d^a, extended somewhat forward of the shaft C, and is there provided with an upper stop-face 4^b 20 which is arranged to contact with the lower face 3^t of the slide-wall c^a when the stop-arm d, (Fig. 7), is moved, or swung, down to the extreme limit of its downward stroke. Thus, arm-stroke-limiting means appurtenant to the slide S may be arranged, substantially as indicated, whereby to limit the 25 working movements of the stop-arm d in each direction.

In the particular arrangement shown in 30 said Figs. 6 and 7, it will be noted that the stop-arm d is not shown provided with any means for properly limiting the down-stroke of said arm except said stop-face 4^b; when, however, some other and suitable down-stroke-limiting means shall be provided for 35 said stop-arm, said forward stop-face 4^b may be omitted. One such another means is illustrated in Fig. 4^a, and consists of an inward projection or arm-stop, 4^c, carried on 40 the arm d and located in a position above a face, as f^t, (Figs. 4^a and 4^b), which thus serves as a stop-face for said purpose. Said stop-face f^t may be the lower face of a recess, as f^s, to be formed in the frame-wall 45 about as shown. In this arrangement, however, the recess f^s need not be extended entirely through said frame-wall, but a partition, or thin wall, as f^t, may be left in place, preferably about as indicated in Fig. 4^a.

In Figs. 4 and 6, said recess f^s of Fig. 4^a, is shown extended through said frame-wall 50 f^a, thereby forming the mortise f^{s₂}, and said inward stop or projection, 4^c, is shown lengthened to form a follower-engaging end, 55 d^a, in position for being engaged by the

usual magazine follower, n, (herein only partially shown), for thereby (in accordance with an old and well-known practice), automatically actuating the stop-arm into its slide-engaging position, whenever the 70 magazine shall become emptied of cartridges. Said magazine and follower, as indicated in the drawing, may be of the ordinary kind, with which auto-loading pistols are now commonly provided.

In the arrangement of Figs. 4 and 6, it will be seen that said lengthened inward projection d^a has two functions, since it serves as a stop device on the down-stroke 75 of the arm d, and serves in connection with the follower n, for upwardly actuating said arm d. The latter function, or mode of use, may be utilized in some instances, if desired, in combination with said forwardly-extended arm-stop 4^b,—Fig. 7,—by simply extending the mortise, f^{s₂}, downwardly to a point where the lower face, as f^t, thereof will become inoperative as a stop-face; this special arrangement or modification is also illustrated in Fig. 7. Also, if preferred, 80 instead of using said forward arm-stop 4^b, a separate arm-stop,—here shown in the well-known form of a pin, f^s,—may be inserted in the frame F, and may be located on the frame directly below the stop-arm d,—see 85 Fig. 7.

Since the shaft-form cross-bar C is itself provided with means whereby said shaft is retained against longitudinal displacement,—see Figs. 5, 5^a,—therefore said stop-arm d does not require to have any means (either as a part or a detail thereof) whereby to hold this arm in place as regards the 90 position thereof laterally of the frame. Accordingly, said stop-arm,—as regards the withdrawal thereof,—is herein shown free 95 of any position-retaining contact with the frame, except as to the use, (in some instances, as described), of a stroke-limiting frame-face, as f^t, Fig. 4^b; or, of a stroke-limiting stop, as f^s,—see Fig. 7. Said stop-arm d, however, when thus dependably supported and held in place by means of said specially constructed arm-carrying shaft-member C, serves to hold said inward projection d^a, thereof in proper coacting position relative to said magazine follower n, (Figs. 4, 6), while said projection has itself no position-retaining means of any kind. Owing to this very simple and effective arrangement, when the slide S is moved to a 100 position (Fig. 2^a), in which the space 2 coincides with said shaft C, then on drawing said shaft outwardly from its seat in the frame, said follower-engaging projection is drawn 105 directly outward from its said working position, and this may be done regardless of the position of the stop-arm d, whether raised, as in Fig. 2, or lowered as in Figs. 1 and 2^a; hence, said withdrawal may be effected, even 110 115 120 125 130

when the magazine is empty, without giving attention to the follower n , and without having first to push down said follower against the force of the magazine spring by 5 which such followers are ordinarily actuated.

In the more complete development of my present invention, which I have described in connection with the principal views Figs. 10 1 to 5^a, the arm-carrying shaft C, not only constitutes a barrel-and-frame-uniting cross-bar, but also serves as a friction member whereby the slide-stop arm, d , is subjected to a regulation or resistance by a force derived 15 from the slide-actuating spring. When such a regulation or control is not desired, said shaft C may be otherwise arranged, as for instance, in the manner illustrated in Figs. 6 and 7. Assuming the barrel and frame 20 to be substantially as in Fig. 4, the barrel lug b' may be held in place in the frame recess a^3 by a cross-bar C², and this bar may have on one end, a point c^3 , projecting slightly at one side of the frame, and may 25 have on the other end a position-limiting head, as c^8 . Between the frame recess a^3 and the magazine chamber m , a shaft-seat is bored at b'' transversely through the frame. In said seat b'' , the shaft C is supported in the position indicated in Figs. 6 30 and 7, so that the side-walls 3^c, 3^{c'}, will engage in the notches formed by the pairs of surfaces c^5-c^4 and c^6-c^7 , respectively, of said shaft, and thereby hold the shaft 35 against longitudinal displacement substantially the same as shown in Fig. 5. Being itself thus held in place, the shaft C carries one end thereof, and exteriorly of the frame, the stop-arm d , which may be provided with 40 the aforesaid inward projection d^2 , and also, when desired, with the forward projection d^3 , so that the arm, thus equipped, will conform to the uses and modes of action already explained in connection with Figs. 1 to 5^a, 45 inclusive. In Figs. 6, 7, however, a further feature is shown, since said forward projection d^3 here extends in part over the end of the cross-bar C², and thus serves to retain said bar securely in place. On first 50 withdrawing the combined shaft and stop-arm, (in the manner already described), said cross-bar C², then may be readily removed,—by being pushed out in an obvious manner,—and the barrel B will thereby be 55 released or disunited, from the frame.

On comparing the views Figs. 4 and 6 with the sectional view Fig. 5, it will be seen that the coaction of the main slide S with the arm-carrying shaft is the same in 60 each of the two arrangements of said shaft relative to the frame and barrel, and that in each instance the slide-wall 3^c engages over the end-face c^4 of the body of the shaft, for thereby holding both shaft and stop-arm in

proper working position. Also, it will be 65 seen that on moving the slide to bring the gate-way space 2 to the shaft position, (as shown, for instance, in Fig. 2^a), the shaft C may then be drawn out in precisely the same manner in each said instance. However, in 70 the said arrangement of Fig. 6, the withdrawal of the shaft C does not disunite the barrel and frame, whereas in the said arrangement of Fig. 4, such shaft-withdrawal does have that effect or result. 75

The space 2, is shown in the drawing as having a form which is usually designated as a "recess"; the rearward face, 3^k, of which is a locking-face for engaging with the face 4^e of the arm-end 4^a, when the slide S is 80 locked in the retracted position thereof shown in Fig. 2. The forward position of said space 2 is shown in Fig. 1, in which the slide S is presumed to be in the "firing position" relative to the frame F; in this 85 position the slide is a shaft-retaining member, as more clearly shown in Fig. 5. Now, by making the length of the stop-arm d from the center of the shaft to the face 4^e, (see Fig. 1), less than the total movement or 90 stroke of said space 2 from its position in Fig. 1 to its position in Fig. 2, it follows that the slide S must be somewhat retracted from its position in Fig. 1 in order to bring said space 2 to the intermediate 95 position shown in Fig. 2^a, where the space 2 can serve as the gate-way through which to draw out the released shaft C.

Thus, by means of the construction and 100 peculiar location of the shaft C relative to the slide-wall 3^c, and the way these parts are organized or combined with the stop-arm, said single space 2 serves the two distinct purposes of a locking recess for the lock-end 4^a of the stop-arm, and of a gate-way space or recess through which to withdraw the shaft by which said stop-arm is carried. In Fig. 2, distances 7 and 7^a 105 respectively represent, (but in a comparative or symbolic manner, only), the stroke of 110 slide S and the relative length, as aforesaid, of the stop-arm d .

When the stop-arm d is to be provided with means for engaging an operable member located within the frame, it will, of 115 course, be necessary for said lever-arm to be extended rearwardly from the cross-shaft a sufficient distance therefor. The sectional plan view Fig. 4, shows such an arrangement, in which said lever-arm d is provided 120 with the inward projection d^2 extending through the opening f^{33} of the frame. In this view the inner end of said projection d^2 is shown in position for engaging with the usual follower as n of the magazine of 125 the firearm. Since said follower, in practice, will be upwardly actuated by a spring, in the ordinary manner, therefore when the

follower rises upwardly to a point for engaging said inward projection d^2 , thereby the lever-arm d will be spring-actuated, for the purpose of raising the locking-face, or 5 lock-end 4^a thereof into contact with the lower side of the slide S, (Fig. 1), so that when the slide is drawn rearwardly to the loading position (indicated in the side view Fig. 2), said lever-arm will be further 10 raised and thus operate as a slide-stop for engaging and holding the slide in said retracted position. Thus the lever-arm d becomes a slide-locking stop-arm automatically actuatable into a position for locking 15 the slide in the rearward position thereof.

In the arrangement of the mechanism herein described, in connection with Figs. 1 to 5^a, the slide-operating spring N, by its rearward pressure against the shoulder 2^c 20 of the barrel B, applies a relatively intense pressure upon the friction-drum surface c^o of the shaft member C, and thereby tends by reason of the friction so produced, to hold the lever-arm d , either in the upward 25 or the downward position as the case may be. Thus said slide-locking member is held at all necessary times under a due restraint against movements toward and from its slide-engaging position, (Fig. 2), by means 30 of a force derived from the slide-spring N, and without requiring any separate spring or other device especially therefor. In order that said spring N may have at all times a full effect, in so applying friction to said 35 arm-shaft C, the barrel-lug b' , is shown in a position free of contact with the cross-wall b^s of the frame, (Fig. 4), thus providing a small space at c^s ; and in view of this arrangement when used, the shaft C should be 40 made of a size sufficiently large to sustain without injury the recoil forces to which this member is subjected. The barrel, therefore constitutes a means whereby the force or pressure exerted by the spring N, is applied to restraining the movement of the 45 slide-stopping lever-arm d .

The cross-bar, or shaft C,—herein generally referred to as a “barrel and frame uniting” means or device,—not only connects 50 the barrel to the frame, but this connection is a direct one, so that said principal members F and B are not merely secured or connected together but are actually “united” by being each attached directly and fixedly, 55 (although attached releasably), to the other; and, this result is attained without the use therefore of any plurality, train or series of members in effecting such uniting of the barrel and frame.

60 Having thus described my invention, I claim—

1. In a firearm, the combination with a frame and a barrel each provided near the rearward end of the barrel with interlock

portions having transversely disposed and 65 alined cross-shaft seats, of a slide having a lock-face and supported for reciprocating movements forwardly and rearwardly on the frame; a slide-actuating spring intermediate to the slide and barrel; a barrel and 70 frame uniting cross-shaft disposed and fitted to be turned in said alined seats while subjected to friction derived from said spring; and a slide-locking arm rigid with 75 said shaft and carried thereby exteriorly of the frame in position for being engaged with said lock-face of the slide by the turning of the shaft under the pressure of said slide-actuating spring.

2. In a firearm, the combination with a 80 frame and a barrel each provided near the rearward end of the barrel with interlock portions having transversely disposed and alined cross-shaft seats, of a slide having a lock-face and retractably supported on the 85 frame; a barrel and frame uniting cross-shaft disposed and fitted to be turned in said alined seats; and a slide-locking arm rigid with said shaft and having a stop-face in position for being swung into engagement 90 with said lock-face of the slide by the turning of said shaft in said alined shaft-seats of the frame and the barrel, whereby the force of the recoil applies a pressure to the shaft for thereby frictionally restraining 95 such turning of the shaft.

3. In a firearm, the combination with a 100 frame having therein a magazine provided with a spring-actuated follower, and with a barrel; of a slide having a lock-face and supported for reciprocating movements on the frame; a slide-actuating spring reacting against the barrel, said barrel and the frame having interlock portions provided transversely with alined cross-shaft seats; 105 a barrel and frame uniting cross-shaft having the body portion thereof disposed and fitted to turn in said alined seats of the frame and barrel; a slide-locking arm rigid with said cross-shaft and carried thereby exteriorly of the frame in position for engaging 110 said lock-face of the slide by the turning of the shaft in said alined shaft-seats of the barrel and frame; and, means operable by the magazine follower for actuating the 115 slide-locking arm into engagement with said lock-face.

4. In a firearm, the combination with a 120 frame and a barrel, each provided near the rearward end of the barrel, with interlock portions having transversely disposed and alined cross-shaft seats, of a slide having a lock-face and supported for reciprocating movements forwardly and rearwardly on the frame; a slide-actuating spring intermediate to the slide and barrel; a barrel and 125 frame uniting cross-shaft disposed and fitted to be turned in said alined seats while

- subjected to friction derived from said spring, said shaft having at the upper side and upon the body portion thereof, a transverse bearing face in a position adjoining 5 one side of the frame; means appurtenant to the slide and in position and arranged for coacting with said transverse bearing face of the cross-shaft for thereby holding the shaft from displacement during one portion 10 of the reciprocating movement of the slide, and for withdrawing from such coacting position during a further movement of the slide; and, a stop-arm carried by said shaft exteriorly of the frame, and having a lock-end 15 in position for being engaged with said lock-face of the slide by swinging the stop-arm and shaft under the pressure of said spring when the slide is retracted.
5. In a firearm, the combination with a frame and with a barrel, of a slide having a lock-face and retractably supported on the frame, said frame and barrel each having near the rearward end of the barrel, interlock portions provided transversely with cross-shaft seats which are cylindrical and alined; a barrel and frame uniting cross-shaft having a cylindrical body portion thereof disposed in said alined seats, and also having on said body portion thereof, a 20 transverse bearing face in a position adjoining one side of the frame; means appurtenant to the slide and in position and arranged for coaction with said transverse bearing face of the cross-shaft and thereby 25 hold the cross-shaft from displacement during one portion of the retraction of the slide, and for withdrawing from such coaction in one position of the slide; a lever-arm carried by said cross-shaft in a position for being swung into engagement with said lock-face by turning the cross-shaft in said alined shaft-seats when the slide is in a retracted position; and, a slide-actuating 30 spring in position and arranged for applying friction to the shaft during the retraction of the slide and by a force transmitted through the barrel and said shaft-seat thereof.
6. In a firearm, the combination with a frame and with a barrel, of a slide having a lock-face and retractably supported on the frame, said frame and barrel each having near the rearward end of the barrel, interlock portions provided transversely with cross-shaft seats which are cylindrical and alined; a barrel and frame uniting cross-shaft having a cylindrical body portion thereof disposed in said alined seats, and also having on said body portion thereof, a 35 transverse bearing face; means appurtenant to the slide and in position and arranged for coaction with said transverse bearing face of the cross-shaft and thereby hold the cross-shaft from displacement during one portion of the retraction of the slide, and for withdrawing from such coaction in one position of the slide; and, a lever-arm carried by said cross-shaft in a 40 position for being swung into engagement with said lock-face by turning the cross-shaft in said alined shaft-seats when the slide is in a retracted position.
7. In a firearm, the combination with a frame and with a barrel, of a slide having a lock-face and retractably supported on the frame, said frame and barrel each having near the rearward end of the barrel, interlock portions provided transversely with cross-shaft seats which are cylindrical and alined; a barrel and frame uniting cross-shaft having a cylindrical body portion thereof disposed in said alined seats, and also having on said body portion thereof, a 45 transverse bearing face in a position adjoining one side of the frame; means appurtenant to the slide and in position and arranged for coaction with said transverse bearing face of the cross-shaft and thereby hold the cross-shaft from displacement during one portion of the retraction of the slide, and for withdrawing from such coaction in one position of the slide; a lever-arm carried by said cross-shaft in a position for being swung into engagement with said lock-face by turning the cross-shaft in said alined shaft-seats when the slide is in a retracted position; and, a slide-actuating spring in position and arranged for applying friction to the shaft during the retraction of the slide and by a force transmitted through the barrel and said shaft-seat thereof.
8. In a firearm, the combination with a frame and with a barrel, of a slide having a lock-face and retractably supported on the frame, said frame and barrel each having near the rearward end of the barrel, interlock portions provided transversely with cross-shaft seats which are cylindrical and alined; a barrel and frame uniting cross-shaft having a cylindrical body portion thereof disposed in said alined seats; coactive means appurtenant to said body portion of the shaft and to the slide and in position and arranged for holding the cross-shaft from displacement during one portion of the retraction of the slide, and for withdrawing from such holding action in one 100 position of the slide; a lever-arm carried by said cross-shaft in a position for being swung into engagement with said lock-face by turning the cross-shaft in said alined shaft-seats when the slide is in a retracted position; and, means for applying friction to said body portion of the shaft during the retraction of the slide.
9. In a firearm, the combination with a frame, of a slide having a lock-face and supported on the frame and having depending side-walls slidably engaging the frame; a barrel in position between the side-walls

of the slide and having an enlarged rearward end; a slide-actuating spring reacting against said enlarged barrel-end, and said rearward barrel-end and the frame having 5 interlock portions provided transversely with alined cross-shaft seats positioned in the frame at a height partly above and partly below the lower edge of one of said side-walls; a barrel and frame uniting cross- 10 shaft having the body portion thereof disposed and fitted to turn in said alined seats of the frame and barrel, and also having said body portion notched for engagement with said one of the side-walls to retain the 15 cross-shaft in place, said shaft retaining side-wall having therein a gate-way space in a position for permitting the withdrawal of the body of the cross-shaft outwardly through said space when the slide is in one 20 position thereof; and, a slide-locking arm rigid with said cross-shaft and carried thereby exteriorly of the frame, and in position and operable for engaging said lock-face of the slide by the turning of the shaft 25 in said shaft-seats of the barrel and frame.

10. In a firearm, the combination with a frame having therein a magazine provided with a spring-actuated follower, of a slide having a lock-face and supported on the 30 frame and having depending side-walls slidably engaging the frame; a barrel in position between the side-walls of the slide and having an enlarged rearward end; a slide-actuating spring reacting against said enlarged barrel-end, and said rearward barrel-end and the frame having interlock portions provided transversely with alined cross-shaft seats positioned in the frame at a height partly above and partly below the 35 lower edge of one of said side-walls; a barrel-and-frame uniting cross-shaft having the body portion thereof disposed and fitted to turn in said alined seats of the frame and barrel, and also having said body portion 40 notched for engagement with said one of the side-walls to retain the cross-shaft in place, said shaft retaining side-wall having therein a gate-way space in a position for permitting the withdrawal of the body of the cross- 45 shaft outwardly through said space when the slide is in one position thereof; a slide-locking arm rigid with said cross-shaft and carried thereby exteriorly of the frame, and in position and operable for engaging said lock-face of the slide by the turning of the shaft 50 in said alined shaft-seats of the barrel and frame; and, means operable by the magazine follower for actuating the slide-locking arm into said engagement with said lock- 55 face.

11. In a firearm, the combination with a frame having transversely therein a cross-shaft seat and also provided with a magazine having a spring-actuated follower, of a

barrel supported at the rearward end thereof 65 on the frame; a bolt-carrier slidable on the frame and having a lock-face; a cross-shaft having the body portion thereof disposed and fitted to be turned in said shaft-seat of the frame and provided with a transverse 70 face; means appurtenant to the slide and in position for engagement with said transverse face thereby to hold the cross-shaft in place, and for releasing the shaft from such holding action when the slide is in one position thereof; and, a slide-locking arm carried by said shaft exteriorly of the frame, and in position and arranged for actuation by the magazine follower into engagement with said lock-face when the slide is in one 75 position thereof.

12. In a firearm, the combination with a frame having transversely therein a cross-shaft seat and also provided with a magazine having an actuated follower, of a barrel supported at the rearward end thereof on the frame; a bolt-carrier slidable on the frame and provided with a side-wall engaging over one side of the frame and having a lock-face, said cross-shaft seat being 85 positioned in the frame at a height partly above and partly below the plane of the lower edge of said side-wall of the slide; a cross-shaft having the body portion thereof disposed and fitted to turn in said shaft-seat 90 of the frame and provided with a transverse surface in position for engagement with the side-wall thereby to hold the cross-shaft in place, and said side-wall having therein a gate-way space in a position for permitting 95 the withdrawal of the body of said shaft outwardly through said space when the slide is in one position thereof; and, a slide-locking arm carried by said shaft exteriorly of the frame and actuatable by the magazine 100 follower into engagement with said lock-face when the slide is in one position thereof.

13. In a firearm, the combination with a frame and a barrel, each having near the rearward end of the barrel, interlock portions provided transversely with alined cross-shaft seats, of a slide supported for a loading stroke on the frame and provided with a depending wall engaging over one 110 side of the frame and there having an inwardly-facing surface of a continuous length less than the loading stroke; a cross-shaft having the body portion thereof disposed and fitted to turn in said alined seats of the frame and barrel, said body portion 115 having a transverse face in position for engaging said inwardly-facing surface of the slide, whereby releasably to hold the cross-shaft against outward movement in said alined seats, said inwardly-facing surface 120 of the depending wall having the continuity thereof limited in one direction to a position for permitting the withdrawal of the 125

body of the cross-bar outwardly past said slide-wall when the slide is in one retracted position thereof; and, a slide-locking arm rigid with said shaft and carried thereby exteriorly of the frame.

14. In a firearm, in combination, a frame having transversely thereof a shaft-seat; a shaft supported in said shaft-seat and carrying rigid therewith and exteriorly of the frame, a stop-arm having a lock-end in position for coaction with the lock-face of a slide; and a breech-slide retractable through a loading stroke from a firing to a loading position on the frame and provided with a lock-face in position for coaction with said lock-end when the slide is retracted to a loading-position, said slide being also provided with a shaft-engaging side-wall having therein a shaft-releasing recess the rearward face of which constitutes said lock-face of the slide.

15. In a firearm, in combination, a frame having transversely thereof a shaft-seat; a shaft having the body portion thereof supported in said shaft-seat and carrying rigid therewith and exteriorly of the frame, a stop-arm having a lock-end in position for coaction with the lock-face of a slide; and a breech-slide retractable through a loading stroke from a firing to a loading position on the frame and provided with a lock-face in position for coaction with said lock-end when the slide is retracted to a loading position, said slide being also provided with a shaft-engaging side-wall having therein a shaft-releasing gate-way space in a position whereby the body of the shaft may be drawn out of said seat and through said gate-way space when the slide is in a retracted position.

16. In a firearm, in combination, a frame having transversely thereof a shaft-seat; a shaft supported in said shaft-seat and carrying rigid therewith and exteriorly of the frame, a stop-arm having a lock-end in position for coaction with the lock-face of a slide; and a breech-slide retractable through a loading stroke from a firing to a loading position on the frame and provided with a lock-face in position for coaction with said lock-end when the slide is retracted to a loading-position, said slide being also provided with a shaft-engaging side-wall having therein a shaft-releasing recess the rearward face of which constitutes said lock-face of the slide, and said stop-arm having a length less than said loading stroke of the slide, whereby such recess receives the lock-end of said shaft-arm when the retracted slide is locked in said loading po-

sition, and also serves as a gate-way space through which the body of said shaft will pass on the withdrawal of the shaft from said shaft-seat while the slide is in a less retracted position.

65

17. In a firearm, in combination, a frame having transversely thereof a shaft-seat and also having a magazine provided with a spring-actuated follower; a shaft having the body-portion thereof supported in said shaft-seat and carrying rigid therewith and exteriorly of the frame, a stop-arm having a lock-end in position for coaction with the lock-face of a slide; a breech-slide retractable through a loading stroke from a firing to a loading position on the frame and provided with a lock-face in position for coaction with said lock-end when the slide is retracted to a loading-position, said slide being also provided with a side-wall in position for directly engaging with the body portion of said shaft and having therein a shaft-releasing recess through which said body portion of the shaft may be withdrawn from said shaft-seat; and, means appurtenant to the stop-arm and follower for actuating the stop-arm into said slide-engaging position.

70

80

85

95

18. In a firearm, in combination, a frame having transversely thereof a shaft-seat and also having a magazine provided with a spring-actuated follower; a shaft having a body-portion which is supported in said shaft-seat and also is provided with a transverse face, said shaft carrying rigid therewith and exteriorly of the frame, a stop-arm in position and arranged for coaction with the lock-face of a slide, a breech-slide retractable through a loading stroke from a firing to a loading position on the frame and provided with a lock-face in position for coaction with said stop-arm when the slide is retracted to a loading-position, said slide being also provided longitudinally thereof with a shaft-engaging face in position for directly engaging with said transverse face on the body portion of said shaft, and having therein a shaft-releasing space the rearward face of which constitutes said lock-face of the slide and through which said body portion of the shaft may be withdrawn from said shaft-seat; and, means appurtenant to the stop-arm and follower for actuating the stop-arm into said slide-engaging position.
